TES PATENT OFFICE.

CHARLES F. RODIN, OF SAN FRANCISCO, CALIFORNIA.

SHOCK-ABSORBER.

974,709.

Specification of Letters Patent. Patented Nov. 1, 1910.

Application filed November 22, 1909. Serial No. 529,233.

To all whom it may concern:

Be it known that I, CHARLES F. RODIN, a citizen of the United States, residing in the city and county of San Francisco and State of California, have invented new and useful Improvements in Shock-Absorbers, of which the following is a specification.

My invention relates to an improved apparatus to compensate for the rebounding action of springs after they have been compressed, such action occurring when the vehicle passes over irregularities in the road surface, and this recoil or rebound being beyond the normal position of the springs is not only disagreeable to the occupants of the vehicle, but is disastrous to the springs themselves.

My invention consists in the combination of parts and details of construction which will be more fully explained by reference to the accompanying drawings, in which—

Figure 1 is an elevation showing an end view of my device, and its connection with the axle and frame of the car. Fig. 2 is a transverse section showing the interior and its attachment to the axle. Fig. 3 is a section in the plane of the axle showing the interior surface of the cylinder. Fig. 4 is a side view of the shaft, and the vane or piston carried thereon.

In my invention, A is a plate of somewhat irregular shape, but in general form having a flat outer surface of sufficient size to receive the circular segment 2, which is provided with flanges 3, and these flanges correspond with similar flanges or extensions upon the part A so that the two may be secured together by bolts and nuts as at 4, with a gasket between to prevent leakage. The segment 2 is closed at each end, and for purposes of easy access, at least one of the ends 5 may be bolted to the segment, as plainly shown in Fig. 1.

The surface of the plate A against which the segment is secured has a longitudinal, semi-cylindrical groove 6, in which the shaft 7 which carries the vane 8, is fitted to oscillate. In the bottom of this groove is a channel 9 which is adapted to receive an elastic packing bar 10. Such packing may be made of any suitable material. I have found that steel or other metal bar slightly arched and fitted into the channel, will form a sufficiently fluid-tight contact with the surface of the shaft 7, so that as the latter oscillates when in action, the joint will be retained

tight, and no leakage will occur at this point.

The vane or piston 8 extends radially from the shaft to the inner periphery of the cylinder segment 2, and it has packing bars 11 fitted into its edges so as to form tight joints between the edge which moves against the interior of the cylinder, and also the ends which move in contact with the ends 5 of the segmental case.

A series of holes 12 is made through the part 8, and upon one side of it these openings are controlled by valves as at 13, these valves opening to allow this part to move freely in one direction, and closing when it commences to move in the opposite direction.

The connection between this apparatus and the car is effected by means of a crank 75 or rocker-arm 14 which is fixed to the end of the shaft 7 exterior to the casing 2, and the end of this rocker-arm is connected by a link 15 with the frame 16 of the car; so that the parts being supported upon the wheel 80 axle, as will be hereafter described, when the car body approaches the axle by reason of the compression of the springs upon which the car frame is supported, this vane or piston 8 will, by reason of its connection 85 with the car frame, be caused to move downwardly toward the lower part of the casing 2. This casing being filled with liquid, the latter will force its way through the openings 12 which are sufficient in number to allow a substantially free movement, and the liquid will then be transferred to the upper part of the casing 2.

When the compression of the springs has been exhausted, and the latter attempt to 95 return to their normal position, means must be provided to allow the liquid to transfer from the upper to the lower part of the case 2. This means consists of a series of grooves or channels 16^a which are made in the curved surface of the case 2. These grooves have collectively a sufficient area to allow the liquid to pass the edge of the vane or piston 8 so that the latter may return to its normal position slowly and in unison with the expansion of the springs.

In order to prevent the springs rebounding so as to pass beyond their normal position, and thus causing an objectionable shock, these grooves or channels are made 110 of different lengths so that when the piston 8 is at its lowest point, all of the grooves

2
 or channels will coincide with the peripheral edge of the piston, and will thus allow the liquid to pass very freely. As the piston rises, the ends of these grooves, which are 5 tapered to a point, are successively cut off, and less liquid passes through the remaining grooves, until at the end of the up-stroke the piston will have passed the last of the grooves, and the liquid then within 10 the upper part of the cylindrical casing will be retained without further means of escape, as the valves 13 will be closed against it. I am thus enabled by the increasing length of the grooves 16 to provide 15 for as free a passage of the liquid around the piston as may be desirable, when the springs first commence to arise from their compressed condition, and to gradually reduce the area through which the liquid may 20 pass until the springs are gradually checked in their upward movement so that no disagreeable rebound or shock occurs. In order to adjustably attach this device to the car axle 17, the inner periphery of the part 25 A is concaved as shown at 18 so as to substantially fit the curvature of the axle 17.

Upon the opposite side of the axle is a segmental clip 19 having a similar curvature and bolts 20 passing through this clip, and 30 through the part A, are provided with nuts by which the parts may be drawn together, and gripped with sufficient force upon the axle.

In order to prevent the accidental turning 35 of the device upon the axle, I have shown one or more set screws or equivalent means 21, for securing the part, and preventing its turning after being clamped. By this means I can turn the device about the axle 40 so that it may stand higher or lower, and when the shaft 7, the arm 14, and link 15, are connected with the frame of the car, the piston-vane 8 will stand either higher or lower in its casing, according to the position

in which the parts are secured to the axle. 45 Thus, if the piston stands low, the compression of the springs will carry it down to the lower part of the casing where the passages 16 are all uncovered by the piston, and the upward movement will be at first, correspondingly free, with a gradual reduction in its speed until the end of the stroke is reached. If set higher in the casing, its 50 limit of downward motion will be correspondingly less, and a less number of grooves 55 16 will be uncovered, and the upward return movement will be correspondingly slower.

Having thus described my invention, what I claim and desire to secure by Letters Patent is—

The combination in a spring recoil compensator, of a plate adapted to be secured to the axle of a vehicle, said plate having a longitudinal segmental groove, a segmental casing having the axis of the groove its center of curvature, a shaft turnable in the groove, a channel formed in the lower part of the groove, a packing bar located in the channel and forming a joint with the surface of the shaft, a piston projecting radially 65 from the shaft and having a packing joint between its edges and the interior of the segmental case, means for oscillating the shaft and piston within the casing, valve-controlled passages by which liquid contained in the casing is allowed to pass freely 70 from one side to the other of the piston, and return grooves formed in the inner surface of the casing, said grooves being gradually lengthened from one end to the other of the 75 casing.

In testimony whereof I have hereunto set my hand in the presence of two subscribing witnesses.

CHARLES F. RODIN.
